(57) **CLAIM**

(**) Term: **15 Years**

The ornamental design for a device for supplying oxygen or other gases to water, as shown and described.

(21) Appl. No.: **29/665,541**

DESCRIPTION

(22) Filed: **Oct. 4, 2018**

FIG. 1 is a top perspective view of a device for supplying oxygen or other gases to water showing our new design; FIG. 2 is a side view of the embodiment of FIG. 1;

Related U.S. Application Data

FIG. 3 is another side view of the embodiment of FIG. 1; FIG. 4 is another side view of the embodiment of FIG. 1 opposite to the view of FIG. 2;

(62) Division of application No. 29/594,045, filed on Feb. 15, 2017, now Pat. No. Des. 834,143.

FIG. 5 is another side view of the embodiment of FIG. 1 opposite to the view of FIG. 3;

(51) **LOC (11) Cl.** **23-01**

FIG. 6 is a top plan view of the embodiment of FIG. 1; FIG. 7 is a bottom plan view of the embodiment of FIG. 1;

(52) **U.S. Cl.** ..... **USPC D23/207**

FIG. 8 is a top perspective view of a second embodiment showing our new design;

(58) **Field of Classification Search**

FIG. 9 is a side view of the embodiment of FIG. 8; FIG. 10 is another side view of the embodiment of FIG. 8;

USPC D23/207, 209; 210/232, 282; D30/106; 261/76

FIG. 11 is another side view of the embodiment of FIG. 8 opposite to the view of FIG. 9;

CPC B01D 35/30; B01D 35/153; B01D 29/111; C02F 1/003; B29C 47/682; A01K 63/045

FIG. 12 is another side view of the embodiment of FIG. 8 opposite to the view of FIG. 10;

See application file for complete search history.

FIG. 13 is a top plan view of the embodiment of FIG. 8; and, FIG. 14 is a bottom plan view of the embodiment of FIG. 8.
